UNITED STATES PATENT OFFICE.

ALFRED L. ROWE, OF ST. LOUIS, MISSOURI, ASSIGNOR TO THE MISSISSIPPI
GLASS COMPANY, OF MISSOURI.

DESIGN FOR SHEET-GLASS.

SPECIFICATION forming part of Design No. 17,737, dated September 20, 1887.

Application filed August 1, 1887. Serial No. 245,901. Term of patent 7 years.

To all whom it may concern:

Be it known that I, ALFRED L. ROWE, a citizen of the United States, residing at the city of St. Louis, in the State of Missouri, have invented and produced a new and original Design for Sheet-Glass, of which the following is a specification, reference being had to the accompanying drawing, forming part thereof.

As shown by the annexed drawing, my design is that of a number of crosses set, respectively, in diamond - shaped outlines. These crosses are placed upon sheets of glass in any suitable manner. The diamond-shaped outlines are ridges in the glass, which are placed

upon the sheets of glass in any suitable manner. 15

I claim—

The configuration of the design exhibited in the annexed drawing when applied to sheet-glass. 20

In testimony whereof I have affixed my signature, in presence of two witnesses, this 22d day of July, 1887.

ALFRED L. ROWE.
